US007628302B2

(12) **United States Patent**
Yau

(10) **Patent No.:** **US 7,628,302 B2**
(45) **Date of Patent:** **Dec. 8, 2009**

(54) **GARMENT HANGER WITH DEPENDENT LOOP AND ACCESSORY HANGER**

(76) Inventor: **Wai Shing Yau**, 179-181, 1/F, Block 2, Yip On Fty. Bldg., Wang Hoi Road, Kowloon Bay, Kowloon (HK)

(*) Notice: Subject to any disclaimer, the term of this patent is extended or adjusted under 35 U.S.C. 154(b) by 0 days.

(21) Appl. No.: **11/535,586**

(22) Filed: **Sep. 27, 2006**

(65) **Prior Publication Data**

US 2007/0158375 A1 Jul. 12, 2007

GARMENT HANGER WITH DEPENDENT LOOP AND ACCESSORY HANGER**CROSS-REFERENCE TO RELATED APPLICATIONS**

This application claims priority to U.S. Provisional Application No. 60/766,351, filed Jan. 12, 2006, entitled "Garment Hanger with Dependent Loop and Accessory Hanger," the contents of which are incorporated herein by reference in its entirety.

TECHNICAL FIELD

This disclosure relates to a hanger, and more particularly to a garment hanger with a dependent loop and an accessory hanger that may be mounted on the dependent loop.

BACKGROUND

Numerous types of hangers have been used to hang garments, such as skirts, slacks, and pants. As is known in the art, hangers typically have a cross-member on which to hang the garment, with a hook coupled to the cross-member for hanging the hanger on a rail or other hanging mechanism.

Some hangers have employed a loop structure on the underside of the cross-member through which another hook may be hung to support another hanging garment. However, these hangers do not have a mechanism that can fixedly secure the added hanger at a stationary position. Rather, the added hanger can rotate freely within the loop.

Some loop hangers use a "coordinated loop" structure to keep the added hanger in a position that is relatively parallel to the top hanger. Exemplary hangers in this respect are shown in U.S. Pat. No. 4,871,098. However, even in this "coordinated loop" design, the additional hanger is loosely attached to the loop hanger, and can be rotated freely when a force is applied to it.

There is a need for a hanger that can be attached to another hanger, while maintaining the position of the additional hanger at a secured position.

BRIEF SUMMARY

A hanger having a dependent loop is provided. The dependent loop may allow an additional hook and associated hanger to be hung therefrom, or an accessory hanger to be attached thereto. The accessory hanger may be secured to the dependent loop by a securing mechanism.

BRIEF DESCRIPTION OF THE DRAWINGS

For a more complete understanding of the principles disclosed herein, and the advantages thereof, reference is now made to the following descriptions taken in conjunction with the accompanying drawings in which:

FIG. 1 is an elevational view of a hanger with dependent loop in accordance with the present disclosure;

FIG. 2 is a perspective view of the dependent loop with an exemplary accessory hanger attached in accordance with the present disclosure;

FIG. 3 and 3A are exemplary embodiments of the dependent loop and the accessory hanger;

FIG. 4 is a bottom view of the dependent loop;

FIG. 5 is an elevational view of an exemplary hanger, with an accessory hanger secured to a dependent loop in accordance with the present disclosure;

2

FIG. 6 is an elevational view of the accessory hanger attached to the dependent loop;

FIG. 7 is an elevational view of the accessory hanger separated from the dependent loop;

FIG. 8a is an elevational view of an accessory hanger separated from a dependent loop according to another embodiment of the present disclosure;

FIG. 8b is a top view of the dependent loop shown in FIG. 8a;

FIG. 9 is an elevational view of a garment hanger having an information mount and a dependent loop in accordance with the present disclosure.

FIG. 10 is an elevational view of a tandem hanger having a dependent loop in accordance with the present disclosure.

FIG. 11 is an elevational view of a pinch-clip accessory hanger having a dependent loop in accordance with the present disclosure.

FIG. 12 is an elevational view of an exemplary accessory hanger having a dependent loop in accordance with the present disclosure.

FIG. 13 is an elevational view of a tandem accessory hanger having a dependent loop in accordance with the present disclosure.

FIG. 14a is a perspective view of another accessory hanger separated from the dependent loop;

FIG. 14b is a perspective view of the accessory hanger of FIG. 14a attached to the dependent loop;

FIG. 15a is an elevational view of an accessory hanger separated from a dependent loop according to another embodiment of the present disclosure;

FIG. 15b is a top view of the accessory hanger of FIG. 15a;

FIG. 16a is an elevational of an accessory hanger engaged with a dependent loop according to another embodiment of the present disclosure;

FIG. 16b is an elevational view of the accessory hanger of FIG. 16a separated from the dependent loop;

FIG. 16c is a perspective view of the accessory hanger of FIG. 16a separated from the dependent loop;

FIG. 17a is an elevational view of an accessory hanger engaged with a dependent loop according to another embodiment of the present disclosure;

FIG. 17b is an elevational view of the accessory hanger of FIG. 17a separated from the dependent loop;

FIG. 17c is a perspective view of the accessory hanger of FIG. 17a separated from the dependent loop;

FIG. 18a is an elevational view of an accessory hanger engaged with a dependent loop according to another embodiment of the present disclosure;

FIG. 18b is an elevational view of the accessory hanger of FIG. 18a separated from the dependent loop;

FIG. 18c is a perspective view of the accessory hanger of FIG. 18a separated from the dependent loop;

FIG. 19a is an elevational view of an accessory hanger engaged with a dependent loop according to another embodiment of the present disclosure;

FIG. 19b is an elevational view of the accessory hanger of FIG. 19a separated from the dependent loop; and

FIG. 19c is a perspective view of the accessory hanger of FIG. 19a separated from the dependent loop.

DETAILED DESCRIPTION

Referring now to FIG. 1, illustrated is an elevational view of a hanger 100 with dependent loop 150. As used herein, the term "loop" refers to any interconnected structure without regard to specific shapes, sizes or configurations. Hanger 100 is capable of holding pants, skirts, shorts, and other garments

or articles. Hanger 100 includes a cross member 110 and a hook member 120 of conventional configuration for hanging on a rail. The cross member 110 may be of I-Beam construction, or any such similar structure providing rigidity. The cross member may be made using vacuum molding or injection molding techniques and may be made of translucent or colored, plastic material. Dependent loop 150 is integrally molded to the cross member, and is typically located in the center of gravity of the hanger 100, for example, on the underside of the hanger, aligned with the hook. Of course, the dependent loop 150 may be connected to the cross member in other suitable manners such as detachable connections. FIG. 2 illustrates a perspective view of a portion of an accessory hanger 200 coupled to dependent loop 150, whereas FIG. 3 shows a perspective view of the dependent loop 150 and the accessory hanger 200 separated from each other.

The dependent loop 150 includes nodules 152, which are disposed on the inside vertical surfaces of the dependent loop 150. Nodules 152 provide a securing mechanism to securely fasten accessory hanger 200 to the dependent loop 150. In the exemplary embodiment illustrated in FIG. 3A, nodule 153 of the dependent loop 150 is a stem with a ball joint mounted at the end. In other embodiments, the nodule 152 may be any other fastening member that may engage with accessory hanger 200. Indeed, the nodule 152 may take the form of a peg, which is designed to pressure fit with a corresponding hole. Other suitable fastening arrangements are contemplated so long as the accessory hanger can be detachably secured to the dependent loop.

The accessory hanger 200 includes an attaching plate 202 integrally molded or otherwise connected to one end of arm 204. The other end of arm 204 is connected to a variety of objects (not shown in FIG. 3) that are operable to hold an accessory garment such as a tie, a pair of gloves, a pair of socks, a pair of shoes, or any other accessory garment.

The attaching plate 202 includes holes 206 and an opening 208. The holes 206 provide an opening through which nodules 152 may enter, and be securely fastened thereto. It is to be appreciated that the holes may be replaced with sockets without departing from the scope of this disclosure. Still further, the attaching plate 202 may include the nodules 152 and the dependent loop may include the holes 206 formed therethrough, such as depicted in FIGS. 15a and 15b. The opening 208 is a gap in the attaching plate 202 that provides sufficient spacing for dependent loop 150. The attaching plate 202 further includes a slot 210 extending from the opening 208. The slot 210 has dimensions that are sufficient to provide clearance to the accessory hanger 200 when attaching it to the dependent loop 150. In some embodiments, the attaching plate 202 is formed of resilient material to permit enlargement of the slot 210 by flexing opposing portions of the attaching plate.

In operation, the accessory hanger 200 may be attached to the dependent loop 150 by inserting the accessory hanger 200 through the lower portion of the dependent loop 150. The accessory hanger may then be rotated toward the nodules 152 and force may be applied to the attaching plate 202 in the appropriate direction to secure nodules 152 to holes 206. As mentioned earlier, nodules 152 and holes 206 may provide a ball and socket combination for securing the accessory hanger 200. Sufficient forces applied in the opposite direction may of course allow the accessory hanger to be released from dependent loop 150.

FIG. 4 shows a bottom view of the dependent loop 150. The lower portion of the dependent loop 150 provides a base from which another hanger may be hung. Thus, the dependent loop 150 provides a multi-functional hanging apparatus which

allows for both hanging conventional hangers and hanging accessory hangers, such as the accessory hanger 200. The reference numeral 254 references a diagonal clearing distance for the slot 210 when in the diagonal configuration.

5 FIG. 5 is an elevational view of the exemplary hanger 100 with accessory hanger 200 (a portion of which is shown) secured thereto via the dependent loop 150. FIGS. 6-7 are detailed elevational views of the accessory hanger 200 attached to the dependent loop 150 (FIG. 6) and the accessory hanger separated from the dependent loop (FIG. 7).

10 FIG. 8a illustrates another exemplary dependent loop 160, which includes nodules 162 disposed on the same vertical surface. In operation, the accessory hanger 200 may be snap fit onto the dependent loop 160 by aligning the holes 206 of the accessory hanger with the nodules 162 and applying pressure to the attaching plate 202 to engage the nodules with the holes. FIG. 8b illustrates a top view of the dependent loop 160.

15 It should be appreciated that the present disclosure can be applied to a wide variety of garment hangers. For example, the present disclosure can be implemented with a single garment hanger as shown in FIG. 5, or it can also be implemented with a garment hanger 300 that has been adapted to receive an information tab or clip mounted thereon, as shown in FIG. 9. The garment hanger 300 includes an information tab mount 302 that is operable to receive an information tab and to inhibit removal of the information tab absent some tool or other removing device. The garment hanger 300 further includes the dependent loop 150 as described above.

20 In yet another example, the present disclosure can be implemented with a tandem hanger arrangement 400 as shown in FIG. 10 of the application. The tandem hanger 400 also includes the dependent loop 150 as described above.

25 It should also be understood that the present disclosure can be applied to a wide variety of accessory hangers. As discussed previously in the present disclosure, one end of arm 204 may be integrally molded or otherwise connected to a variety of objects that are operable to hold an accessory garment. For example, a pinch clip hanger 500 may be mounted or integrally molded to the arm 204 as illustrated in FIG. 11. The pinch clip hanger 500 may also include the dependent loop 150 as described above.

30 FIG. 12 illustrates yet another embodiment of an accessory hanger 600 in accordance with the present disclosure. In this embodiment, attaching plate 202 replaces the hook of a typical garment hanger. Accessory hanger 600 may also have the dependent loop 150 to allow the attachment of an additional accessory hanger. FIG. 13 illustrates a tandem garment hanger converted into a tandem accessory hanger 700 in a similar fashion.

35 FIGS. 14a and 14b illustrate yet another embodiment of the present disclosure in which an accessory hanger 800 includes a traditional hook portion 802. In this example, the hook portion 802 is substantially semi-circular in shape and includes at least one hole 804 for receiving the nodule 152 in a secured engagement. In practice, the nodule 152 may be snap fit into the hole 804. In another embodiment, two holes may be provided to further effect a secured attachment. It is to be appreciated that other similar arrangements can also be employed without departing from the teachings of the present disclosure.

40 FIGS. 15a and 15b illustrate yet another embodiment of the present disclosure in which an accessory hanger 900 includes an attachment plate 902 for attaching to a dependent loop 250. The attachment plate 902 includes nodules 904 disposed on opposing sides of the attachment plate. The nodules 904 correspond to holes 252 formed through the dependent loop

250. In operation, the accessory hanger 900 may be attached to the dependent loop 250 by inserting the accessory hanger 900 through the lower portion of the dependent loop 250. The accessory hanger may then be rotated toward the holes 252 and force may be applied to the attaching plate 902 in the appropriate direction to secure nodules 904 to holes 252.

FIGS. 16a-16c illustrate yet another embodiment of the present disclosure in which an accessory hanger 1000 includes a hook portion 1002 for engagement with a dependent loop 350. In this embodiment, the dependent loop 350 includes three legs 352, 354, 356, of which legs 352 and 354 extend posteriorly (as viewed in FIGS. 16a-16c) of leg 356. As illustrated in FIGS. 16b-16c, the dependent loop 350 and hook portion 1002 include complimentary structure to provide a secured engagement therebetween. In particular, the hook portion 1002 includes a pair of holes 1004 formed through the hook portion and disposed substantially about a nodule 1006 extending from the hook portion. The dependent loop 350 includes a pair of nodules 360, at least one of each being disposed on legs 352 and 354, thereby providing an engagement structure for the corresponding holes 1004. In addition, the dependent loop includes a hole 362 formed through the leg 356 for receiving the corresponding nodule 1006 extending from the hook portion 1002. Of course, any combination of holes/nodules may be used to provide a secured engagement between the hook portion 1002 and the dependent loop 350. The hook portion 1002 further includes a slot 1008 for permitting access of the hook portion 1002 over a base portion 364 of the dependent loop 350. In practice, the hook portion 1002 is directed over the base portion 364 in the direction shown by the arrow in FIG. 16c. The hook portion 1002 is then engaged with the dependent loop 350 via the holes/nodules arrangement discussed above.

FIGS. 17a-17c illustrate yet another embodiment of the present disclosure in which the accessory hanger 1000 includes the hook portion 1002 for engagement with the dependent loop 350. In this embodiment, the accessory hanger 1000 and dependent loop 350 have alternate structure for providing the secure engagement therebetween. In particular, the accessory hanger 1000 has been modified to include a hole 1004 formed through the right side (as viewed in FIG. 17b) of the hook portion 1002 and a nodule 1006 disposed on a surface of the left side (as viewed in FIG. 17b) of the hook portion. The dependent loop 350 includes complimentary structure to receive the accessory hanger 1000 in a secure engagement. In particular, the dependent loop 350 includes a nodule 360 formed on leg 354 and a hole 362 formed through leg 352, thereby providing an engagement structure for the corresponding hole 1004 and nodule 1006. Of course, any combination of holes/nodules may be used to provide a securing engagement. The hook portion 1002 further includes a slot 1008 for permitting access of the hook portion 1002 over a base portion 364 of the dependent loop 350. In practice, the hook portion 1002 is directed over the base portion 364 in the direction shown by the arrow in FIG. 17c. The hook portion 1002 is then engaged with the dependent loop 350 via the holes/nodules arrangement discussed above.

FIGS. 18a-18c illustrate yet another embodiment of the present disclosure in which an alternative accessory hanger 1100 may be engaged with the dependent loop 350. In this embodiment, the accessory hanger 1100 includes an attaching portion 1102 having an inverted T-slot 1108 formed therein. The attaching portion 1102 includes a hole 1104 formed through the right side (as viewed in FIG. 18b) of the attaching portion 1102 and a nodule 1106 disposed on a surface of the left side (as viewed in FIG. 18b) of the attaching

portion. The dependent loop 350 includes a nodule 360 formed on leg 354 and a hole 362 formed through leg 352, thereby providing an engagement structure for the corresponding hole 1104 and nodule 1106. Of course, any combination of holes/nodules may be used to provide a securing engagement. In practice, the attaching portion 1102 is directed over the base portion 364 in the direction shown by the arrow in FIG. 18c. The attaching portion 1102 is then engaged with the dependent loop 350 via the holes/nodules arrangement discussed above.

FIGS. 19a-19c illustrate yet another embodiment of the present disclosure in which the accessory hanger 1000 may be engaged with an alternative dependent loop 450. In this embodiment, the dependent loop 450 includes four legs 452, 454, 456 and 458 extending from the cross member (not shown) and terminating in a base portion 460. The dependent loop 450 and hook portion 1002 include complimentary structure to provide a secured engagement therebetween. In particular, the hook portion 1002 includes a hole 1004 formed through the left side of the hook portion (as viewed in FIG. 19b) and a nodule 1006 extending from the hook portion and disposed right of the hole 1004 (as viewed in FIG. 19b). The dependent loop 450 includes a nodule 462 disposed on leg 452 and a hole 464 formed through leg 458, thereby providing an engagement structure for the corresponding hole and nodule of the hook portion 1002. Of course, any combination of holes/nodules may be used to provide a securing engagement. The hook portion 1002 further includes a slot 1008 for permitting access of the hook portion 1002 over the base portion 460 of the dependent loop 450. In practice, the hook portion 1002 is directed over the base portion 460 in the direction shown by the arrow in FIG. 19c. The hook portion 1002 is then engaged with the dependent loop 450 via the holes/nodules arrangement discussed above.

While various embodiments of a garment hanger with a dependent loop and associated accessory hangers according to the apparatus and principles disclosed herein have been described above, it should be understood that they have been presented by way of example only, and not limitation. Thus, the breadth and scope of the invention(s) should not be limited by any of the above-described exemplary embodiments, but should be defined only in accordance with any claims and their equivalents issuing from this disclosure. Furthermore, the above advantages and features are provided in described embodiments, but shall not limit the application of such issued claims to processes and structures accomplishing any or all of the above advantages.

Additionally, the section headings herein are provided for consistency with the suggestions under 37 CFR 1.77 or otherwise to provide organizational cues. These headings shall not limit or characterize the invention(s) set out in any claims that may issue from this disclosure. Specifically and by way of example, although the headings refer to a "Technical Field," such claims should not be limited by the language chosen under this heading to describe the so-called technical field. Further, a description of a technology in the "Background" is not to be construed as an admission that technology is prior art to any invention(s) in this disclosure. Neither is the "Brief Summary" to be considered as a characterization of the invention(s) set forth in issued claims. Furthermore, any reference in this disclosure to "invention" in the singular should not be used to argue that there is only a single point of novelty in this disclosure. Multiple inventions may be set forth according to the limitations of the multiple claims issuing from this disclosure, and such claims accordingly define the invention(s), and their equivalents, that are protected thereby. In all instances, the scope of such claims shall be

considered on their own merits in light of this disclosure, but should not be constrained by the headings set forth herein.

What is claimed is:

1. A garment hanger operable to receive an attaching hanger, the attaching hanger having an attachment plate, the attachment plate having first and second openings defined therethrough, the garment hanger comprising:

a cross member; and

a loop member depending downwardly from the cross member, the loop member cooperating with the cross member to form a closed loop;

wherein the loop member further comprises:

a first portion defining a first opposing surface lying in a first plane and having a first nodule extending therefrom;

a second portion defining a second opposing surface lying in a second plane and having a second nodule extending therefrom; and

a third portion disposed between the first and second portions, the third portion connecting the first and second opposing surfaces, whereby the first and second opposing surfaces are spaced apart such that the first nodule extends towards the second plane and the second nodule extends towards the first plane;

wherein the first and second portions define first and second longitudinal axes, respectively, and the first and second longitudinal axes are not parallel, whereby the first and second nodules are operable to be received by the first and second openings of the attachment plate of the attaching hanger, respectively; and

wherein the nodules each comprise a stem with a ball joint mounted on the stem.

2. A garment hanger according to claim 1, wherein a plurality of nodules are disposed on one surface of the loop member.

3. A garment hanger according to claim 1, further comprising an arm extending upwardly from the cross member towards a second cross member, wherein the first and second cross members are connected in a tandem arrangement.

4. A garment hanger according to claim 3, further comprising a second arm extending upwardly from the second cross member, the second arm having an attaching plate connected thereto.

5. A garment hanger according to claim 1, wherein the first and second planes are parallel to each other.

6. A method for mounting a first hanging apparatus to a second hanging apparatus, the method comprising:

providing a first hanging apparatus having a cross member and a loop depending downwardly from the cross member, wherein the loop defines a pair of opposing surfaces each having at least one hole formed therethrough;

providing a second hanging apparatus, the second hanging apparatus having an arm and an attaching plate connected to the arm, wherein the attaching plate includes a plurality of nodules disposed thereon, a centrally disposed opening, and a slot extending from the opening; and

inserting the attaching plate over a portion of the loop via the slot, rotating the attaching plate to align the holes with the nodules, and exerting force on the attaching plate to secure the nodules to the holes.

7. A garment hanger operable to receive an attaching hanger, the attaching hanger having an attachment plate, the attachment plate having first and second openings defined therethrough, the garment hanger comprising:

a cross member; and

a loop member depending downwardly from the cross member, the loop member cooperating with the cross member to form a closed loop;

wherein the loop member further comprises:

a first portion defining a first opposing surface lying in a first plane and having a first nodule extending therefrom;

a second portion defining a second opposing surface lying in a second plane and having a second nodule extending therefrom; and

a third portion disposed between the first and second portions, the third portion connecting the first and second opposing surfaces, whereby the first and second opposing surfaces are spaced apart such that the first nodule extends towards the second plane and the second nodule extends towards the first plane;

wherein the first and second portions define first and second longitudinal axes, respectively, and the first and second longitudinal axes are not parallel, whereby the first and second nodules are operable to be received by the first and second openings of the attachment plate of the attaching hanger, respectively; and

wherein the nodules each comprise a peg.

8. A garment hanger according to claim 7, wherein a plurality of nodules are disposed on one surface of the loop member.

9. A garment hanger according to claim 7, further comprising an arm extending upwardly from the cross member towards a second cross member, wherein the first and second cross members are connected in a tandem arrangement.

10. A garment hanger according to claim 9, further comprising a second arm extending upwardly from the second cross member, the second arm having an attaching plate connected thereto.

11. A garment hanger according to claim 7, wherein the first and second planes are parallel to each other.

12. A garment hanger, comprising:

a cross member; and

a loop member depending downwardly from the cross member, the loop member cooperating with the cross member to form a closed loop;

wherein the loop member further comprises:

a first portion having proximal and distal ends and defining a first opposing surface therebetween lying in a first plane, wherein the first portion has a first nodule extending from the first opposing surface, and the proximal end of the first portion is directly connected to and thereby abuts the cross member;

a second portion having proximal and distal ends and defining a second opposing surface therebetween lying in a second plane, wherein the second portion has a second nodule extending from the second opposing surface, and the proximal end of the second portion is directly connected to and thereby abuts the cross member; and

a third portion directly connected to the distal ends of the first and second portions, the third portion connecting the first and second opposing surfaces, whereby the first and second opposing surfaces are spaced apart such that the first nodule extends towards the second plane and the second nodule extends towards the first plane; and

wherein the nodules each comprise a peg.

13. A garment hanger according to claim 12, wherein a plurality of nodules previously presented are disposed on one surface of the loop member.

14. A garment hanger according to claim **13**, further comprising an arm extending upwardly from the cross member towards a second cross member, wherein the first and second cross members are connected in a tandem arrangement. 5

15. A garment hanger according to claim **14**, further comprising a second arm extending upwardly from the second cross member, the second arm having an attaching plate connected thereto. 10

16. A garment hanger according to claim **12**, wherein the first and second planes are parallel to each other. 15

17. A garment hanger according to claim **16**, wherein the first and second portions define first and second longitudinal axes, respectively, and the first and second longitudinal axes are not parallel. 20

18. A garment hanger, comprising:

a cross member; and

a loop member depending downwardly from the cross member, the loop member cooperating with the cross member to form a closed loop; 25

wherein the loop member further comprises:

a first portion having proximal and distal ends and defining a first opposing surface therebetween lying in a first plane, wherein the first portion has a first nodule extending from the first opposing surface, and the 30

proximal end of the first portion is directly connected to and thereby abuts the cross member;

a second portion having proximal and distal ends and defining a second opposing surface therebetween lying in a second plane, wherein the second portion has a second nodule extending from the second opposing surface, and the proximal end of the second portion is directly connected to and thereby abuts the cross member; and

a third portion directly connected to the distal ends of the first and second portions, the third portion connecting the first and second opposing surfaces, whereby the first and second opposing surfaces are spaced apart such that the first nodule extends towards the second plane and the second nodule extends towards the first plane; and

wherein the nodules each comprise a stem with a ball joint mounted on the stem.

19. A garment hanger according to claim **18**, wherein the first and second planes are parallel to each other. 20

20. A garment hanger according to claim **19**, wherein the first and second portions define first and second longitudinal axes, respectively, and the first and second longitudinal axes are not parallel.
